DESIGN FOR A TABLE

Peter M. Wege, East Grand Rapids, Mich., assignor to Metal Office Furniture Company, Grand Rapids, Mich., a corporation of Michigan

Application May 13, 1933. Serial No. 48,099

Term of patent 7 years

To all whom it may concern:

Be it known that I, PETER M. WEGE, a citizen of the United States, residing at No. 2630 Lake Drive, S. E., East Grand Rapids, in the county of Kent and State of Michigan, have invented a new, original, and ornamental Design for a Table, of which the following is a specification, reference being had to the accompanying drawing, forming a part thereof, in which:—

The figure is a perspective view of a table, the

supporting column being the essential feature of the design and shown in full lines, the remaining portions comprising the base and the top being shown in dotted lines and indicating non-essential features.

I claim:

The ornamental design for a table having a supporting column of the design shown and described.

PETER M. WEGE.
